United States Patent Office

Des. 232,735
Patented Sept. 10, 1974

232,735

MAGNETIC DISK MODULE

John Orville Kinsey, Morgan Hill, Bernard William McVey, Saratoga, and David Graham Moore, Richard Burke Mulvany, and Philip Cleer Yenerich, San Jose, Calif., assignors to International Business Machines Corporation, Armonk, N.Y.

Filed Mar. 12, 1973, Ser. No. 340,402

Term of patent 14 years

Int. Cl. D14—02
U.S. Cl. D26—5 C

FIG. 3

FIG. 1 is a front perspective view of a magnetic disk module showing our new design;

FIG. 2 is a rear perspective view thereof; and

FIG. 3 is a bottom view thereof.

We claim:

The ornamental design for a magnetic disk module, as shown.
